FIG- 4

FIG- 5

FIG. 6

FIGURE 1 is a side elevational view of a portable combined sound and picture reproducing apparatus showing my new design;

FIGURE 2 is an elevational view of the opposite side thereof;

FIGURE 3 is a top plan view thereof;

FIGURE 4 is a right end view thereof;

FIGURE 5 is a left end view thereof; and

FIGURE 6 is a bottom plan view thereof.

The broken-line showing of a record disk in FIGURES 1 and 2 are for illustrative purposes only.

This application is a continuation-in-part of application Serial No. D.82,294 filed on October 23, 1964, now abandoned.

I claim:

The ornamental design for a portable combined sound and picture reproducing apparatus, as shown and described.
